UNITED STATES PATENT OFFICE.

OTTO H. REMMERT, OF AUSTIN, TEXAS.

INDICATING APPARATUS FOR THE SPARK-PLUGS OF HYDROCARBON-ENGINES.

1,187,178.

Specification of Letters Patent. Patented June 13, 1916.

Application filed March 30, 1915. Serial No. 18,085.

To all whom it may concern:

Be it known that I, OTTO H. REMMERT, a citizen of the United States of America, residing at Austin, in the county of Travis and State of Texas, have invented new and useful Improvements in Indicating Apparatus for the Spark-Plugs of Hydrocarbon-Engines, of which the following is a specification.

10 This invention relates to improvements in finding apparatus for the spark plugs of hydrocarbon engines and has particular application to finding apparatus of the class described for use in conjunction with starting mechanism.

In carrying out the present invention, it is my purpose to provide finding apparatus for the spark plugs of hydrocarbon engines whereby the operator of a motor vehicle may 20 readily and quickly ascertain which spark plug is connected in circuit with the timer so that a charge of gasoline may be delivered to the cylinder equipped with such spark plug whereby the priming charge may 25 be exploded to start the engine and enable the latter to pick up its own cycle of operation.

It is also my purpose to provide finding apparatus of the class described whereby a 30 spark may be produced between the terminals of any spark plug irrespective of the brush and contacts of the timer so that in the event of the brush being out of engagement with the contacts of the timer and the 35 priming charge delivered to one of the cylinders, the spark plug of such cylinder may be energized to ignite the priming charge, thereby enabling the engine to be started without the usual cranking operation.

40 A further object of my invention is to provide finding apparatus of the type set forth which may be readily and quickly installed in a motor vehicle and connected up with the ignition system of the hydrocarbon engine 45 of such vehicle; and wherein the component parts will be so arranged and correlated as to reduce the possibility of derangement to a minimum.

With the above and other objects in view, 50 the invention consists in the construction, combination and arrangement of parts hereinafter set forth in and falling within the scope of the claims.

In the accompanying drawings; Figure 1 55 is a diagrammatic view of finding apparatus constructed in accordance with the present

invention, the same being shown connected up with the ignition system of a hydrocarbon engine. Fig. 2 is a view in front elevation of the switch. Fig. 3 is a rear elevation of the same. Fig. 4 is a longitudinal sectional view through the switch. Fig. 5 is a cross sectional view on the line 5—5 of Fig. 3. Fig. 6 is a perspective view of the movable element of the indicator. Fig. 7 is a diagrammatic plan view of starting mechanism used in connection with the finding apparatus, parts being shown in section.

Referring now to the drawings in detail, A designates the ignition system of a hydrocarbon engine, such system embodying spark plugs a' , a^2 , a^3 and a^4 , vibrator coils b having the secondary windings thereof connected with the spark plugs respectively, a timer c having the contacts thereof connected with the primary windings of the respective vibrator coils b and the brush or roller thereof grounded, the battery d having one side thereof tapped onto the ground connection of the timer roller and the other side connected to one contact of a two-way switch e , and a magneto f having one side tapped onto the ground connection of the timer roller and the other side connected to the remaining contact of the two-way switch e , 85 the pivot blade of the switch e being connected to the remaining terminals of the vibrator coils b . The spark plugs are grounded upon the engine while the remaining terminals of the secondary windings of the vibrator coils, that is, the terminals remote from those connected with the spark plugs, are tapped onto the respective primaries of the vibrator coils, as is usual in this type of ignition system. As this particular style 90 of ignition system is old and well known, it is believed that the above description thereof is sufficient and therefore a more extended description is eliminated.

My improved finding apparatus embodies 100 a switch B comprising a body in the form of a slab 1 preferably composed of insulating material and formed with a rearwardly projecting marginal flange 2. Secured to the rear face of the slab 1 adjacent 105 to the upper end thereof is a segmental contact strip 3 and disposed below the strip 3 concentrically of the center of the arc of the strip are contacts 4 spaced apart equal distances and fastened to the back face of 110 the slab in some suitable manner. Formed in the slab 1 concentrically of the circle de-

scribed by the strip 3 and contacts 4 is an opening 5 and rotatably mounted within the opening 5 is a receptacle 6 preferably composed of insulating material and having the inner end thereof closed and formed with a peripheral flange 7 engaging in a circular groove 8 formed in the rear face of the slab 1 contiguous to the inner end of the opening 5. Secured to the rear end of the receptacle 6 at diametrically opposite points are sector-like strips 8' formed, respectively with outwardly projecting fingers 9, 10 diametrically opposed and adapted to engage the segmental strip 3 and the contacts 4 respectively, the finger 10 being movable into engagement with any one of the contacts 4, while the finger 9 rides upon the strip 3. The end wall of the receptacle 7 is equipped with a contact 11 and disposed within the receptacle is a threaded shell 12 and the contact 11 and shell 12 are connected by way of wires 13 with the respective sector-like strips 8 and threaded into the shell 12 is the butt of a signal lamp 14, the terminals 25 of the lamp 14 being electrically connected with the contact 11 and shell 12 respectively. The front end of the receptacle 6 projects beyond the front face of the slab 1 and surrounding the projecting end of the receptacle and suitably fixed thereto is a collar 15 formed with a radially projecting indicating finger 16 by means of which the receptacle may be revolved within the opening 5 to move the finger 10 into engagement 30 with any one of the contacts 4. The outer face of the slab 1 concentrically of the circular path of the finger 16 is provided with indicating marks 17 corresponding in number with the contacts 4 and indicative of the 35 positions of the respective contacts so that by moving the finger 16 into registration with one of the marks 17 the finger 10 will be engaged with the corresponding contact 4, thereby electrically connecting the segmental strip 3 and the particular contact 4 by way of the finger 9, strip 8, lamp filament, the remaining strip 8 and the finger 10, the lamp filament being connected in series with the bridged segmental strip and 40 contact. Formed in the slab 1 adjacent to the lower end thereof and spaced apart across the slab are openings 18 corresponding in number with the contacts 4 and slidably mounted within the respective openings 18 are plungers 19 having the inner ends thereof equipped with heads 20 seating in recesses 21 formed in the back face of the slab contiguous to the inner ends of the respective openings 18. Fastened to the 45 rear face of the slab below the openings 18 is a ground plate 22 and formed on the ground plate 22 and projecting upwardly therefrom are spring contact fingers 23 having the upper ends thereof terminating at the rear of the plungers 19 respectively and

in engagement with the heads 20 of such plungers, while fastened to the back face of the slab above the respective openings 18 are contacts 24 projecting downwardly and having the lower end portions thereof offset and spaced apart from the confronting portions of the respective fingers 23. Thus, the fingers 23 are normally out of engagement with the contacts 24 and when any one of the plungers 19 is pressed inwardly against the resistance of the spring finger 23, the latter is actuated into engagement with the companion contact 24. The contacts 24 are connected, respectively, with the contacts 4 by way of fusible wires 25. 50

In the present instance, the rear edge of the flange 2 at opposite points is formed with recesses 26 and these recesses 26 are adapted to receive lugs 27 formed upon the opposite edges of a closure plate 28. The 55 plate 28 is movable into the space between the walls of the flange 2 and when in this position the lugs 27 engage in the recesses 26 and are held therein by means of suitable binding screws that are passed through openings in the lugs and into the adjacent portion of the flange 2. The inner face of this closure plate 28 is preferably formed with grooves 29 designed to receive the various contacts, contact fingers, etc., on the rear face of the slab 1 so that the elements on the rear face of the slab will be segregated from each other in order to avoid short circuiting and the like. 60

In accordance with my present invention, 100 the contacts 24 are connected by means of wires 30 with the timer terminals of the vibrator coils respectively, that is, to say, the terminals of the primary windings of the vibrator coils connected with the stationary 105 contacts respectively of the timer, and the segmental contact strip 3 of the switch is connected by way of a conductor 31 with the blade of the switch *e*, while the plate 22 is grounded upon the engine as at 32 to 110 correspond with the grounded side of the battery *d* of the ignition system. By means of this construction and arrangement, it will be seen that when the switch *e* is on the battery connection and the receptacle 6 rotated to engage the contact finger 10 with the contacts 4 successively, the filament of the lamp 14 will be energized when the finger 10 engages the contact 4 corresponding to the contact of the timer that is engaged by the roller or brush of the timer, and as the contacts 4 are arranged to correspond with the plugs in the cylinders, the driver of the vehicle will be advised of the cylinder in which the plug connected with the timer is located. For instance, should the roller of the timer be on the contact connected with the plug *a*, and the contact finger 10 in engagement with the contact 4 connected with the primary winding of the 115 120 125 130

vibrator coil connected with such timer contact, and the switch *e* closed, current will flow from one side of the battery *d* through the switch *e*, conductor 31, contact strip 3, contact finger 9, contact strip 8, the filament of the lamp 14, the remaining contact strip 8, the contact finger 10, the particular contact 4 engaged by such finger, the wire 30, the connection between the wire 30 and 10 said timer contact, the brush or roller of the timer and back to the battery, as clearly illustrated in Fig. 1 of the drawings. Thus, the lamp will be energized and the operator notified that the spark plug *a*² is connected 15 with the roller of the timer. A primary charge may now be injected into this cylinder under pressure.

Should the contact roller be in a position between two adjacent contacts of the timer, 20 the lamp 14 will remain deenergized in the movement of the contact finger 10 over the contacts 4. However, the operator may energize any one of the spark plugs by pushing the corresponding plunger 19, or 25 all of the plugs may be energized simultaneously by depressing all of the plungers. For instance, should the operator depress the plunger corresponding to the plug *a*² and the blade of the switch *e* be on the 30 battery contact current will flow from one side of the battery *d* through the primary winding of the coil corresponding to the plug *a*², the conductor 30, the contact 24 connected to the conductor 30, the contact 35 finger 23, ground plate 22, ground 32, and back to the other side of the battery by way of the grounded terminal thereof. Thus, a current will be induced in the secondary winding of the coil connected with the plug 40 *a*², such current flowing from one side of the secondary winding of such coil, through the plug *a*², the ground, through the timer *e* and back to the other side of the secondary winding through the connection between 45 the timer and the primary winding of the coil connected with the plug *a*².

In the present embodiment of my invention, I have shown the spark plug finding apparatus as used in conjunction with a 50 starting mechanism comprising a tank 33 located upon the dashboard of the vehicle within the vision of the operator and having the upper end thereof provided with a filling opening 34 and the front wall thereof 55 of equipped with a gage glass 36 whereby the quantity of gasoline in the tank may be at all times determined. Disposed within convenient reach of the driver of the vehicle is an appropriate form of pump 36 and 60 connected with the outlet of the pump 36 is a tube 37 connected with one end of a pipe 38 and the remaining end of the pipe 38 is connected with a manifold 39. Leading from the outlet of the tank 33 is a pipe 65 40 provided with a cut-off cock 41 and this

pipe 40 is tapped into the pipe 38. Leading from the manifold 39 are tubes 42 corresponding in number with the cylinders of the engine and connected with such cylinders respectively and each tube 42 is provided with a cut-off cock 43. If desired, the ends of the tubes leading into the respective cylinders may be connected with priming spark plugs 44. In practice, previous to the energization of the spark plug in the particular cylinder, the cock 43 in the tube 42 connected with such cylinder is opened and the cock 41 opened to permit a quantity of gasoline to flow into the pipe 38 and then closed. The pump 36 is now 70 operated and forces the gasoline and air through the pipe 38, manifold 39, the open valve 43 and the tube 42 into the cylinder and the gasoline and air enter the cylinder in the form of a combustible mixture so that when the spark is produced in the cylinder, this mixture which is under pressure, due to the pump 36, is exploded. Each tube 42 is preferably equipped with a check valve 45 adjacent to the particular cylinder 75 so as to prevent back flow of the mixture 80 into the tube.

From the foregoing description taken in connection with the accompanying drawings, the construction, mode of operation and manner of employing my invention will be readily apparent. It will be seen that I have provided apparatus whereby the spark plug connected with the roller of the timer may be located or found and then energized 95 to explode a priming charge in the particular cylinder so that the engine may be started and enabled to pick up its own cycle of operation; and whereby a spark may be produced in any or all of the cylinders independently of the timer so that 100 priming charges in the cylinders may be exploded irrespective of the position of the timer brush or roller with respect to the contacts.

If desired, all of the cocks 43 may be 110 opened so that a priming charge will be delivered to each cylinder of the engine.

While I have herein shown and described the preferred form of my invention by way of illustration, I wish it to be understood that I do not limit or confine myself to the precise details of construction herein described and delineated, as modification and variation may be made within the scope of 115 the claims without departing from the spirit of the invention.

I claim:

1. In finding apparatus for the spark plugs of hydrocarbon engines, the combination with the ignition system of the engine, of contacts connected with the timer terminals of the vibrator coils respectively, a switch element movable over said contacts and connected with the spark coil side of 125 130

the battery of the ignition system, and a signal connected in circuit with said element and adapted to be energized when the element engages the contact in circuit with the roller on the timer.

2. In finding apparatus for the spark plugs of hydrocarbon engines, the combination with the ignition system of the engine, of contacts connected with the timer terminals of the vibrator coils respectively, a switch element movable over said contacts and connected with the spark coil side of the battery of the ignition system, and a signal lamp connected in circuit with said element and carried by the latter and adapted to be energized when the element engages the contact in circuit with the roller on the timer.

3. In finding apparatus for the spark plugs of hydrocarbon engines, a switch comprising a contact connected with the battery terminals of the controlling switch of the ignition system, contacts connected with the timer terminals of the vibrator coils respectively and spaced apart, a movable switch element having a portion normally engaging the first-mentioned contact and the remaining portion adapted to engage the last-mentioned contacts independently of one another, and a signal connected in circuit with the first-mentioned contact and adapted to be energized when the first-mentioned contact and the particular second-mentioned contact connected with the timer roller are bridged.

4. In finding apparatus for the spark plugs of hydrocarbon engines, a switch comprising a contact connected with the battery terminals of the controlling switch of the ignition system, contacts connected with the timer terminals of the vibrator coils respectively and spaced apart, a movable switch element having a portion nor-

mally engaging the first-mentioned contact and the remaining portion adapted to engage the last-mentioned contacts independently of one another, a signal connected in circuit with the first mentioned contact and adapted to be energized when the first-mentioned contact and the particular second-mentioned contact connected with the timer roller are bridged, and indicating means associated with said movable switch element to indicate the particular timer contact engaged by the timer roller.

5. In finding apparatus for the spark plugs of hydrocarbon engines, a switch comprising a contact connected with the battery terminals of the controlling switch of the ignition system, contacts connected with the timer terminals of the vibrator coils respectively and spaced apart, a movable switch element having a portion normally engaging the first-mentioned contact and the remaining portion adapted to engage the last-mentioned contacts independently of one another, a signal connected in circuit with the first-mentioned contact and adapted to be energized when the first-mentioned contact and the particular second-mentioned contact connected with the timer roller are bridged, contacts connected to the last-mentioned contacts respectively, contact fingers grounded upon the engine and capable of movement into engagement with said last-mentioned contacts respectively, and means for moving said fingers into engagement with the respective last-named contacts substantially as, and for the purpose, described.

In testimony whereof I affix my signature in presence of two witnesses.

OTTO H. REMMERT.
